UNITED STATES PATENT OFFICE.

HARRY C. SMITH, OF ARLINGTON, MASSACHUSETTS, ASSIGNOR TO BLAKE ELECTRIC MFG. COMPANY, OF BOSTON, MASSACHUSETTS, A CORPORATION OF MASSACHUSETTS.

SELVAGE-OPENING DEVICE.

Application filed September 2, 1924. Serial No. 735,325.

The present invention is concerned with a device or machine for opening and spreading out the selvage edges on webs of cloth which have become folded over during the processes of dyeing, washing, drying, or otherwise finishing the cloth. The webs of cloth, both cottons and woolens, in passing through the finishing operations, and over or under the rolls by which they are guided in their course through the finishing apparatus, frequently become doubled over at their selvage edges throughout greater or less distances. This is particularly the case with woolen goods when coming to the drier after being washed. The lengths of the folds thus occurring are variable and their disposition and frequency are irregular. In some parts of its length, the web will be flat from edge to edge. In other parts there will be an overturned fold at one edge, and some times there will be folds at both edges, irregular in the characteristics of length, width, spacing, etc.

Heretofore in practice these folded over edges have been opened and spread out by hand, operators being stationed beside each edge of the traveling web of cloth watching for doubled places at the edges and using their fingers to open the doubled over parts and spread them out flat. This is tedious and tiresome work, particularly in the case of woolen goods where the folded over stretches cling tenaciously, due to the felting and interlocking of the fibers which occurs when the goods are wet and when they are subjected to pressure.

I am aware that it has been proposed to do this work automatically by providing, adjacent to a tenter frame or other machine for operating on cloth, a blade or blades bearing against a face of the cloth, or both opposite faces, and crossing the edge or edges of the cloth obliquely, and designed to turn back folded over parts and flatten out puckered parts of such edges. Nevertheless, such automatic opening devices have not gone into use, so far as I have been able to learn, but in the commercial art the universal practice has been to open the folded selvages manually. The reason for the practical failure of said proposals is, I believe, to be

found in the following facts and conclusions.

When cloth is carried through the finishing operations, it is customary to sew the ends of lengths or webs of cloth together so that there may be a continuous progression of the cloth and each preceding length may draw the foremost end of the next length after it through the various parts of the machine. The seams by which the lengths of cloth are thus connected are hastily and roughly made and project to some distance from the surface of the cloth. Such a seam, passing the blades of the opening device, would catch on the blade at that side of the cloth to which the seam projects if the blades, or a blade and a complemental support for the cloth were held at the slight distance apart necessary for the purpose of opening the doubled edges and were not deliberately separated far enough to let the seams pass; from which it would happen that, either the cloth would be torn or one of the blades would become bent or broken.

With this condition in view the object and accomplishment of my invention have been to provide, in combination with blades suitably constructed and arranged to turn back and flatten rolled or puckered selvages, means to effect a separation of the blades when such a seam is about to pass between them, and to cause their return to working position after the seam has passed. The invention comprises such combination and the several parts thereof, together with their equivalents as will more fully appear from the following specification.

I will now describe, with reference to the drawings, an apparatus embodying my invention and illustrating the principles thereof. Such apparatus exhibits the invention in the form which I now prefer to use, but since other constructions and arrangements embodying the same invention and included within the scope of the appended claims may be used this apparatus is to be considered as an illustration and not a limitation of the invention.

In the drawings—

Figure 1 is a side view of the apparatus above referred to, in its relation to the cloth on which it operates; the cloth being shown

in edge view and guide rolls for the cloth being shown in cross section.

Figure 2 is an elevation of the apparatus as seen from the line 2—2 of Figure 1 looking toward the right from such line.

Figure 3 is a perspective view showing the manner in which the opener blades operate on the cloth.

Like reference characters designate the 10 same parts in all of the figures wherever they occur.

As I have mentioned before, the apparatus particularly embodying this invention may be mounted in a variety of situations and in connection with various machines, 15 tenter frames or other machines. It may, for instance, be mounted on some part of a drier in position to act on the cloth going into the drier. In these drawings, then, I 20 have merely shown the apparatus in operative relation to a web of cloth, but without attempting to show the details of any specific mounting. In other words, the mounting here shown is diagrammatic and 25 illustrates simply a possible means for operatively supporting the apparatus. Thus the numerals 4 and 5 designate rolls mounted on any suitable frame 6 and over which a web of cloth 7 passes in being treated. These 30 rolls may be guide rolls or propeller rolls in any machine having to do with the manufacture or treatment of cloth.

The devices for opening the folds which occur more or less frequently along the 35 selvage edges of the cloth web consist preferably of two blades 8 and 9 which lie opposite to each other adjacent to the top and bottom sides, respectively, of the web and bear against the faces of the cloth, preferably with substantial pressure in order that, 40 no matter how thin the cloth may be or how irregular in thickness, the extremities of the blades will be able to pass between the folded over edge and the main body of the web. Each blade supports the cloth against 45 the pressure of the other, and thus combines in one structure means having the functions, respectively, of supporting the cloth and of flattening out its folded or puckered edge. 50 The operative parts of the blade extend outward from a position inside the edge of the web and terminate just short of, or at, such edge, as shown in Figures 2 and 3, or may extend across such edge, if desired, and be 55 arranged at any desired suitable angle to the direction in which the cloth travels. These 60 extremities are fine enough to enter within such an edge fold, even though the same lies close to the web and is firmly felted to the body of the web, but are not sharp enough to cut the cloth. They are also suitably 65 formed to turn over and spread out flat the curled over edge after entering within the same.

15 In Figure 3 the part numbered 10 repre-

sents a part of the selvage edge curled over and folded back against the top side of the cloth. As the cloth is traveling in the direction of the arrow *a*, the blade 8 is in condition to pass under the fold or flap 10 and is 70 formed to open and spread out such flap. In like manner the blade 9 is arranged and adapted to turn out a fold or flap on the under side of the web.

These blades are carried by holders 11 and 75 12 supported by a suitable bracket 13, the latter being secured to the frame 6. As here shown the holders 11 and 12 are bars supported at a distance outside of the edge of the cloth, extending from their points of 80 support partly over the cloth and then curved toward the cloth and outward in such manner as will form and locate the blades with the characteristics and in the positions previously described. The bar 12 85 is secured to the bracket 13 and on the bar is mounted a post 14 to which there is pivoted at 15 a block 16 carrying the bar 11. However, equivalents of these constructions may 90 be otherwise made if desired.

A spring 17, formed as a helix surrounding and guided by a pin 18, which is secured to the bar 12 and passes through the bar 11, tends to separate the bars and blades, or rather to lift the bar 11 and blade 8, as 95 shown by dotted lines in Figure 2. An electromagnet 19 supported on the bar 12, when energized, attracts an armature 20 attached to bar 11 and then brings the blades together as shown by solid lines in all the figures. 100

The magnet coils of the electromagnet are connected in circuit with a source of electric energy, indicated diagrammatically in Figure 1 as a generator 21, and with a stationary 105 switch contact 22 and with a switch lever 23, said switch lever carries a flexible and resilient switch arm 24 adapted to cooperate with said contact. The conductors are indicated diagrammatically at 25, 26, 27 and 28. The conductor 28 is connected to the movable switch lever and to the conductor 26 through a binding screw 29. Said binding screw and the switch contact 22 are mounted in a stationary base plate 30 which is supported over the web of cloth by means of a block or post 31 secured to the bracket 13, and a bracket 32 secured to said post 31, as shown in Figure 2. There is also secured to the switch base 30 a bar 33, forming with 110 said base plate a frame structure, to one end of which is pivoted the switch lever 23 and to the other end of which is pivoted a secondary lever 34 connected to the switch lever by a link or connecting rod 35. 115

The switch lever has an arm 36 extending toward the cloth and substantially in contact therewith and the lever 34 extends toward and substantially in contact with the cloth. These levers are at opposite sides of the 120 125 130

opener blades. They may be directly over the guide rolls 4 and 5, respectively, or over some other cloth supporting means, or the cloth may be stretched so taut between the 5 rolls that it will not sag under them. At any rate the switch lever and the secondary lever are so arranged, and the cloth is so held, that when any seam, as 37, between the connected ends of two successive pieces of 10 cloth, passes the lever arm 36, it will move said arm from the full line position shown in Figure 1 to approximately that shown in dotted lines in the same figure. And when the same seam passes the secondary 15 lever 34, it will move the latter from the dotted line position to the full line position shown in Figure 1. The connecting rod 35 is so attached at respectively opposite sides of the pivots of these levers that it transmits 20 movement from one to the other, but with reversed direction. Hence the seam, in passing the switch lever, opens the switch, and in passing the secondary lever 34, causes the switch to be closed. While the switch is 25 opened the magnet, of course, is dead and the spring 17 is then permitted to separate the blades and provide space enough between them to permit passage of the seam without damaging the machine or the cloth. 30 The above described mechanism is one of two duplicate but reverse mechanisms or devices which in practice are applied adjacent to the opposite edges of the cloth web.

Various modifications and rearrangements 35 of the essential parts herein disclosed may be made within my contemplation and the scope of the protection which I claim. Generically the apparatus comprises a suitable selvage opening device, and preferably a 40 pair of cooperating devices at opposite sides of the web, each of which supports the web and holds it against the other, combined with automatic means controlled by a seam in the cloth for displacing one or both of the openers when a seam passes, and means for returning the opener or openers to operative 45 position after the seam has passed by. That phase of the invention which comprises an electromagnet and opposed yielding means for so displacing the openers under the control of a seam operated switch, may be modified in ways equivalent to the embodiment of the invention herein described, and within the scope of my generic claims.

50 This selvage opening apparatus, and its equivalents may be mounted and arranged in connection with various machines for operating on cloth.

What I claim and desire to secure by Letters Patent is:

55 1. A means for automatically opening the selvages of cloth comprising a blade located close to the surface of a traveling web of cloth and arranged with its outer extremity near the edge of such web, combined with

means for withdrawing said blade from the cloth when a seam in the cloth passes by.

2. An apparatus for opening folds in the selvage edges of cloth webs comprising supporting means outside of the edge of a 70 traveling cloth web, an opener blade holder extending over the cloth and across its edge, and an opener blade connected with said holder and extending thence toward the surface of the web and outwardly toward the 75 edge of the web; combined with means for withdrawing said blade from the surface of the web when a seam between two connected webs passes by.

3. An apparatus for opening the selvages 80 of cloth webs comprising a supporting structure adjacent to the location of a traveling cloth web, blade holders extending over said supporting structure across the adjacent edge of the cloth at opposite sides of the web, 85 opener blades carried by said holders and arranged to engage opposite faces of the web in position to enter and turn back folded portions of the adjacent edge, means tending to hold said holders and blades in close proximity to the web, and means controlled by the passage of a seam connecting two webs for causing a separation between said blades when such seam passes them.

4. An apparatus for opening the selvages 90 of cloth webs comprising opener blades suitably supported opposite to each other adjacent to the edge of a traveling cloth web and with provision for such web to pass between them, electromagnetic and mechanical 100 means associated with said blades, one of said means tending to bring the blades together toward the cloth and the other being operative to separate them, the electromagnetic means being more powerful than the 105 mechanical means, and a switch arranged in the circuit of said electromagnetic means for opening and closing said circuit and being arranged for operation by a seam between two connected webs.

5. An apparatus for opening the selvages 110 of traveling cloth webs comprising two opener blades arranged opposite to each other adjacent to the edge of a traveling web of cloth and at opposite sides of such web, 115 said blades being constructed to open and spread out a folded over portion of the edge, a spring acting on said blades tending to separate them, an electromagnet coupled with said blades and of more powerful effect 120 than said spring operative, when energized, to bring them together, and a switch in the circuit of the electromagnet operated by seams between connected webs of cloth to break said circuit when such seams pass the 125 opener blades.

6. The combination with opener blades of the character set forth, of electromagnetic means and spring means associated with said blades and acting oppositely upon them, one 130

- of such means tending to bring the blades together and the other to separate them, the electromagnetic means being more powerful in effect than the spring means, a switch 5 for opening and closing the circuit of said electromagnetic means, said switch having an arm arranged adjacent to the path of a web of cloth, arranged to be moved in one direction by the passage of a seam connecting two webs together, and a secondary 10 lever spaced apart from the switch lever in the direction of movement of the web, arranged to be similarly moved in the same manner by such seam and connected with the switch lever to impart reversed movement to the latter when so moved.
7. An apparatus for opening the selvages of cloth webs comprising opener blades situated at opposite sides and near the edge 15 of a traveling web of cloth, said blades being separable from one another, an electromagnet coupled to said blades and tending, when energized, to bring them nearer together, a spring having a less powerful effect than said magnet engaged with the blades and tending to separate them, a switch in the circuit of the magnet having an arm arranged in position to be engaged and moved so as to break the circuit, by the passage 20 of a seam connecting two webs together, and a secondary lever arranged to be subsequently moved by the same seam in a manner to cause closing of the circuit by such switch.
8. A means for automatically opening the curled selvage of a cloth web comprising a blade located close to the surface of a traveling web of cloth and arranged in such proximity to the edge of the web that it 25 will turn out folds occurring in such edge, said blade being movable toward and away from the surface of the cloth, and seam controlled means arranged and operable to cause such separation of the blade from the cloth 30 when a seam in the web passes by.
9. An apparatus for opening the curled selvages of cloth comprising means for supporting and propelling a web of cloth, a blade located and arranged in such proximity to the surface and to an edge of the web that it is able to turn out folds occurring in said edge, the blade and web support being relatively movable apart so as to effect 35 a separation between the web and the blade, opposing means associated with said blade and respectively tending to cause separation between the blade and the cloth and to cause approach of the blade and the cloth together, the means tending to cause such approach 40 being of superior force to the separating means when the apparatus is in normal operation, and means controlled by a seam in the cloth approaching the blade for causing a reversal in the relative forces exerted by 45 said means respectively.
10. An apparatus for opening the curled selvages of cloth comprising means for supporting and propelling a web of cloth, a blade located and arranged in such proximity to the surface and to an edge of the web that it is able to turn out folds occurring in said edge, the blade and web support being relatively movable apart so as to effect a separation between the web and the blade, electromagnetic and mechanical means associated with said blade and support, one of said means tending to bring the blade and cloth together and the other being operative to separate them, the electromagnetic means being more powerful than the mechanical 70 means, and a switch arranged in the circuit of said electromagnetic means for opening and closing said circuit and being arranged for operation by a seam between two connected webs. 75
11. An apparatus for opening the curled selvages of cloth comprising means for supporting and propelling a web of cloth, a blade located and arranged in such proximity to the surface and to an edge of the web that it is able to turn out folds occurring in said edge, the blade and web support being relatively movable apart so as to effect a separation between the web and the blade, electromagnetic and yielding mechanical 80 means acting in opposition to one another between said blade and the web support, one of said means tending to effect a separation and the other to effect approach between the cloth web and the blade, and the electromagnetic means being more powerful than the mechanical means, and circuit controllers for said electromagnetic means located at opposite sides of the blades in position to be moved by a seam in the travelling web of cloth, one of said circuit controllers being operable by such seam to open the electromagnetic circuit, and the other to be similarly operated to close said circuit. 85
12. An apparatus for opening the curled selvages of cloth comprising means for supporting and propelling a web of cloth, a blade located and arranged in such proximity to the surface and to an edge of the web that it is able to turn out folds occurring in said edge, the blade and web support being relatively movable apart so as to affect a separation between the web and the blade, and an electromagnet associated with said blade and operative to move the blade toward the surface of the web, a spring of less force than said magnet acting on said blade with tendency to separate it from the cloth, and a circuit controller for said magnet arranged to be moved by a seam in the web 100 and operative when so moved to open the magnet circuit. 105
- In testimony whereof I have affixed my signature.

HARRY C. SMITH.
